INKING MECHANISM FOR PRINTING
PRESSES

Joseph E. Meyer, Westerly, R. I., assignor to C. B. Cottrell & Sons Company, Westerly, R. I., a corporation of Delaware

Application June 16, 1948, Serial No. 33,267

4 Claims. (Cl. 101—350)

1

The object of my invention is to provide a novel means, operable while the press is running, for changing the amount of ink fed by an ink fountain roll, which is driven continuously at a variable surface speed, to one or more ductor rollers oscillating at a constant rate, thereby eliminating the usual tedious re-setting of the large number of fountain adjusting screws when a change in the ink feed is required.

My invention includes an ink fountain, a fountain roll which is driven continuously at a varying surface speed, and one or more ductor rollers oscillating at a constant rate.

My invention also includes means for driving the fountain roll continuously at a varying surface speed, the variation occurring once for every ductor roller oscillation.

My invention also includes a manually controlled means for changing the timed relationship of the different fountain roll surface speeds to the constant ductor roller oscillation for altering the length of contact between the fountain roll and the ductor roller or rollers.

My invention also includes a pair of elliptical gears in the fountain roll drive for driving the fountain roll continuously at a varying surface speed.

My invention also provides a manually controlled means including a differential gearing in the fountain roll drive for changing the timed relationship of the different fountain roll surface speeds to the ductor roller oscillation rate.

A practical embodiment of my invention is represented in the accompanying drawings in which:

Fig. 1 represents a side elevation of the ink fountain;

Fig. 2 represents a horizontal section taken in the plane of the line II—II of Fig. 1, looking in the direction of the arrows;

Fig. 3 represents a vertical section taken in the plane of the line III—III of Fig. 2, looking in the direction of the arrows;

Fig. 4 represents a vertical section taken in the plane of the line IV—IV of Fig. 2, looking in the direction of the arrows;

Fig. 5 represents a vertical section taken in the plane of the line V—V of Fig. 2, looking in the direction of the arrows;

Fig. 6 represents a vertical section taken in the plane of the line VI—VI of Fig. 2, looking in the direction of the arrows; and

Fig. 7 represents a detail vertical section, on a smaller scale, through the ink distribution.

The ink distribution is shown as including an ink fountain 1, a fountain roll 2 which rotates continuously at a varying surface speed, an ink

cylinder 3, one or more, in the present instance two, ductor rollers 4 and 5 which oscillate at a constant rate between the fountain roll 1 and the ink cylinder 3, and groups of distribution rollers 6, 6 which serve to transfer the ink in regulable quantities from the ink cylinder 3 to the form cylinder 7, which form cylinder coacts with the impression cylinder 8 of the press to print on a traveling web (not shown). The fountain roll stud shafts 9 and 10 are rotatably mounted in the uprising ends of the ink fountain 1.

The ductor roller 4 is mounted in corresponding arms 11 of two rock levers pivoted on a cross shaft 12, the other corresponding arms 13 of the rock levers carrying cam rollers 14. The ductor roller 5 is similarly rotatably mounted in corresponding arms 15 of two rock levers pivoted on a cross shaft 16, the other corresponding arms 17 of the rock levers carrying cam rollers 18.

20 The gear 19 of the main press drive is shown as rotatably mounted on a stud axle 20 projecting from the gear side frame 21. This gear 19 drives a gear 22 whose hub 23 is rotatably mounted on another stud axle 24 projecting from the gear side frame 21 in alinement with the fountain roll stud shafts 9 and 10. This gear 22 drives a gear 25 fixed on one end of a cross shaft 26 which is rotatably mounted in both the gear side frame 21 and the work side frame 27. The other end of the cross shaft 26 has fixed thereto a gear 28 which drives a gear 29 whose hub 30 is fixed to a cross shaft 31 rotatably mounted in the work side frame 27 and a work side frame bracket 32, the said shaft 31 being also in alinement with the fountain roll stud shafts 9 and 10.

35 The ductor rollers 4 and 5 are oscillated at a constant predetermined rate as follows: the cam rollers 14 carried by the corresponding arms 13 of the rock levers which control the oscillation of the ductor roller 4 run in the grooves of a pair of box cams 33, one of the cams 33 being fixed to the hub 23 of the gear 22 and the other cam 33 being fixed to the hub 30 of the gear 29. Similarly the cam rollers 18 carried by the corresponding arms 17 of the rock levers which control the oscillation of the ductor roller 5 run in the grooves of a pair of box cams 34, both of the cams 34 being fixed to their adjoining cams 33. The means for driving the ink fountain roll 2 continuously at a variable surface speed each rotation of the fountain roll is shown as comprising the following elements: one bevel gear 35 of a differential gearing is fixed on the constant speed cross shaft 31. The opposite gear 36 of the differential is fixed on the hub of an elliptical gear 37 which is rotatably mounted on the said cross shaft 31. A rotatably adjustable frame

55

38 carries one or more intermediate bevel gears 39, in the present instance two of such gears, which mesh with and operably connect the bevel gears 35 and 36. The elliptical gear 37 meshes with an elliptical gear 40 which is fixed on the outer end of a short cross shaft 41 mounted in the bearing bracket 42 on the work side frame 27, and also in the work side frame bracket 32. The inner end of this cross shaft 41 is provided with a gear 43 which drives the fountain roll gear 44 through an intermediate gear 45. It will be understood that the elliptical gears 37 and 40 are timed to run turn for turn with the ductor roller motion.

The manually operated means for adjusting the rotative speed of the fountain roll 2 with respect to the ductor roller motion, for supplying more or less ink to the ductor rollers 4 and 5 without resorting to the manipulation of the usual fountain screws 46, is as follows:

The rotatable adjustable frame 38 is provided with a toothed sector 47 which meshes with a worm 48 whose shaft 49 is mounted in a housing 50 on the side frame bracket 32. This worm shaft 49 may be turned by any suitable device, as, for instance, a hand crank 51, shown in dotted lines in Figs. 1 and 3. The turning of this worm shaft 49 serves to rock the toothed sector 47 of the frame 38 and thereby the bevel gears 39 to change the rotative positions of the elliptical gears 37 and 40 without affecting the variable speed of the continuously rotating fountain roll, whereby the timed relationship of the high and low surface speeds of the fountain roll 2 to the constant oscillation of the ductor rollers 4 and 5 may be changed to alter the length of contact dwell between the fountain roll and the ductor rollers, thus changing the amount of ink fed to the ductor rollers each rotation of the fountain roll and oscillation of the ductor rollers. It will be understood that this manual adjustment of the fountain roll can be made while the press is running.

While I have shown and described this ink distribution as provided with two ductor rollers, it is obvious that one only of these ductor rollers and its operating mechanism may be employed, if so desired.

Also while I have shown and described the manually controlled means for changing the timed relationship of the different fountain roll surface speeds to the constant ductor roller oscillation, as a hand crank directly connected to the worm shaft, it is obvious that any type of motor, as hydraulic, pneumatic or electric motor may be included for turning the worm.

It is also obvious that various changes may be resorted to in the construction, form and arrangement of the various elements without departing from the spirit and scope of my invention and hence I do not wish to be limited to the particular embodiment herein shown and described.

What I claim is:

1. In a printing press inking mechanism, an ink fountain, a fountain roll, an ink cylinder, 65 one or more ductor rollers oscillating at a constant rate into and out of contact with the fountain roll and the ink cylinder, means including a pair of elliptical gears for driving the fountain roll continuously at a varying surface speed to 70 change the amount of ink fed thereby to the ductor roller or rollers, and a manually controlled means including a differential gearing located in the fountain roll drive for changing the timed relationship of the different fountain

roll surface speeds to the constant ductor roller oscillation, to alter the length of contact dwell between the fountain roll and ductor roller or rollers.

5. In a printing press inking mechanism, an ink fountain, a fountain roll, an ink cylinder, one or more ductor rollers oscillating at a constant rate into and out of contact with the fountain roll and the ink cylinder, and means including 10 a pair of elliptical gears for driving the fountain roll continuously at a varying surface speed to change the amount of ink fed thereby to the ductor roller or rollers, and a manually controlled means for changing the timed relationship of the high and low surface speeds of the fountain roll to the constant ductor roller oscillation, to alter the length of contact dwell between the fountain roll and ductor roller or rollers, said manually controlled means including a differential gearing located in the fountain roll drive and a worm and gear connection with the differential gearing.

3. In a printing press inking mechanism, an ink fountain, a fountain roll, an ink cylinder, one or more ductor rollers oscillating at a constant rate into and out of contact with the fountain roll and the ink cylinder, means including 25 a pair of elliptical gears for driving the fountain roll continuously at a varying surface speed to change the amount of ink fed thereby to the ductor roller or rollers, a differential gearing located in the fountain roll drive and including an intermediate gear, its rotatable frame having a toothed sector, and manually controlled means including a worm meshing with the toothed sector for changing the timed relationship of the high and low speeds of the fountain roll to the constant ductor roller oscillation, to alter the length of contact dwell between the fountain roll and ductor roller or rollers.

4. In an inking mechanism for printing presses, an ink fountain, a fountain roll, an ink cylinder, one or more ductor rollers, and a driving means for oscillating the ductor roller or rollers at a constant rate into and out of contact with the fountain roll and the ink cylinder and for driving the fountain roll continuously at a variable surface speed to change the amount of ink fed thereby to said ductor roller or rollers, said driving means including a constant speed shaft located in axial alinement with the fountain roll, a variable speed shaft geared to the fountain roll, an elliptical gear rotatably mounted on the constant speed shaft and a meshing elliptical gear fast on the variable speed shaft, and a manually controlled differential gearing operatively connecting the constant speed shaft to the first-named elliptical gear for changing the timed relationship of the high and low speeds of the fountain roll to the constant ductor roller oscillation, to alter the length of contact dwell between the fountain roll and ductor roller or rollers.
